James N. Tyler

J. W. Patterson
Design for floor cloth
Patented. April 5. 1859.

UNITED STATES PATENT OFFICE.

JAMES PATERSON, OF ELIZABETH, NEW JERSEY.

DESIGN FOR FLOOR-CLOTH.

Specification forming part of Design No. 1,091, dated April 5, 1859.

To all whom it may concern:

Be it known that I, JAMES PATERSON, of the city of Elizabeth, in the county of Union and State of New Jersey, have invented or produced a Design or Figure to be Printed or Stamped upon Floor Oil-Cloths or other Fabrics; and I do hereby declare that the following is a full and exact description of the same, viz:

The highest or central part of the pattern is drawn to represent a hexagonal table of plain color, which lies upon an octagonal table of shaded colors. These octagonal tables are separated from each other by ornamented bands of color darker than themselves. These bands are separated at their intersections by

dark grounds which are ornamented by rosettes of colors unlike the table and bands, so arranged as to produce a bright and pleasing effect, the whole being shown by the accompanying drawing, which is referred to as forming part of this specification.

What I claim, and desire to secure by Letters Patent of the United States, is—

The above-described arrangement of ornamental figures forming a design, as shown by the accompanying drawing.

JAS. PATERSON.

In presence of—

JAMES B. BURNET,

A. M. ELMER.
